UNITED STATES PATENT OFFICE

THOMAS H. KINMAN, OF BILTON, NEAR RUGBY, ENGLAND, ASSIGNOR TO GENERAL ELECTRIC COMPANY, A CORPORATION OF NEW YORK

RADIO RECEIVING CIRCUITS

Application filed September 12, 1927, Serial No. 219,083, and in Great Britain September 14, 1926.

The present invention relates to radio receiving circuits, and more particularly to a receiving circuit which is adapted selectively to receive in turn signals of a plurality of 5 different wave lengths.

In a receiver of this kind, when used within a certain radius of a station transmitting at one of the wave lengths which the receiver is adapted to receive, interference is frequently 10 experienced when receiving on another wave length, even if the latter differs considerably from that used by the station situated near to the receiver, and it is the object of the present invention to eliminate, as far as possible, this 15 interference.

According to the invention, the receiving system includes a plurality of tuned input circuits, means being provided whereby one or more of the said circuits may be utilized 20 alternatively either as a receiving circuit, or as rejector circuit. The tuned circuits are usually associated either inductively or directly with the aerial or like circuit, and I preferably employ a switching arrangement 25 whereby one of the tuned circuits can be disconnected from the aerial circuit when reception on the wave length to which that circuit is tuned is not desired, and to connect that circuit in the aerial circuit so that it forms a 30 rejector circuit when reception on another wave length is desired. The rejector circuit thereby prevents interference from occurring, due to the transmitting station operating at the wave length to which the rejector circuit 35 is tuned.

In one form of receiving arrangement embodying the invention, the aerial-earth circuit contains two tuned circuits in series, each of which is tuned to one of the wave lengths it 40 is desired to receive. A switch is arranged to connect the aerial circuit in the desired manner to the input circuit of a valve or other arrangement for detecting the received impulses. In one position of the switch, one 45 of the tuned circuits is short-circuited, while the other circuit is connected across the grid and filament of the valve. In the other position of the switch, the tuned circuit, which in the first position was short-circuited, is connected across the grid-filament circuit of the 50

valve, while the other tuned circuit remains in series in the aerial circuit.

This arrangement, and various detail modifications thereof, is more particularly adapted for receiving on alternative wave-lengths 55 which are widely separated. In order to receive selectively signals of neighboring wave-lengths in accordance with the invention, I employ an arrangement in which the tuned circuits are connected in parallel to the common aerial system, the detecting or amplifying device being connected to the aerial system in such manner that a maximum signal response is given by one tuned circuit, while a minimum response is given by the other tuned 60 circuit, which, nevertheless, functions to absorb signal energy of the frequency to which it is tuned, so as to eliminate interference from that frequency.

A switch is provided as before so that the 65 function of the circuits as receptor or rejector circuits can be reversed. In order that the signal response shall be a maximum for one circuit, and a minimum for the other, it is necessary to connect the detecting device, 70 (when this is voltage operated), across the inductive portion only of the tuned circuits. In this way, the capacitive portions of these 75 circuits are so connected that the circuit not in use for receiving purposes functions as a 80 rejector circuit, and gives a minimum signal response in the detector.

In a case where one or both of the tuned 85 circuits consists of inductance in parallel with capacity, it is necessary to connect the 90 circuits through a capacity, and sometimes also through an inductance, the purpose of which is to prevent the tuning of one circuit affecting the tuning of the other circuit. When both the capacity and inductance are 95 coupled in this manner, they may be so tuned as to be resonant to a third frequency, in which case the switching arrangement can be so connected as to render the arrangement capable of receiving at a third frequency, the other two tuned circuits then functioning as 100 rejector circuits.

In either of the above arrangements, the usual reaction coil can be included, a variable coupling being provided between the re- 105

action coil and the tuned circuits. The tuned circuits, however, must be sufficiently removed or screened from one another to avoid interaction between the two circuits.

5 It is important that the inductance and capacity variation of the tuned circuits should be correctly proportioned and related to one another in order to avoid undesirable interaction, and, where parallel circuit arrangements are employed, precautions must be taken to prevent appreciable shunting of energy from one circuit to the other.

15 In order that the invention may be fully understood, reference is directed to the accompanying drawings, wherein Figs. 1 to 3 relate to embodiments of my invention which are of particular utility when the receiver is situated near one transmitting station and at a distance from another transmitting station; and Figs. 4 to 9 relate to further modifications of my invention.

20 Referring to the accompanying drawings, Fig. 1 thereof shows a receiving arrangement in accordance with the invention, in which the aerial-earth circuit AE contains two tuned circuits L_1C_1 and L_2C_2 in series, each of which is tuned to one of the wave lengths it is desired to receive. A switch S is arranged to connect the aerial circuit in the desired manner to the input circuit of a valve V or other arrangement for detecting the received impulses. In position (1) of the switch, the tuned circuit L_2C_2 is short-circuited, while the other tuned circuit L_1C_1 is connected across the grid and filament of the valve. In position (2) of the switch, the tuned circuit L_2C_2 , which in the first position was short-circuited, is connected across the grid-filament circuit of the valve, while the other tuned circuit L_1C_1 remains in series in the aerial circuit.

25 In operating the receiver, the switch S is first put in position (2) in which the more distant station is to be received, i. e., the circuit L_2C_2 which in position (1) is short-circuited, is tuned in the usual manner. Interference from the local station is then suppressed by tuning the other circuit L_1C_1 , which is in series with the aerial, so that it acts as a rejector to the undesired signal. Upon the switch being thrown to the alternative position (1), the rejector circuit L_1C_1 , which has already been tuned to the local or interfering station, is connected in circuit 30 for reception, whilst the other tuned circuit L_2C_2 is short-circuited.

35 The fact that the resonant value of the rejector circuit is slightly different when it is used for reception is not important as the tuning of this circuit in any case will not be critical.

40 It will, of course, be obvious that the two tuned circuits may be interchanged, so that either may function as the rejector circuit.

45 Referring to Fig. 2 in which a modified

form of Fig. 1 is shown, the circuit L_1C_1 functioning as a rejector circuit is included in the input circuit of the valve V, instead of in the aerial circuit, and in addition to this modification a compensating condenser K is included across the circuit L_1C_1 when it acts as a rejector circuit, the value of the condenser K being adjusted so that the resonant frequency of the tuned circuit is the same when it acts either as the tuned input circuit, or as the rejector circuit. When it acts as a rejector circuit, the additional condenser compensates for the natural capacity of the aerial, which is removed when receiving on the alternative wave length. If desired, an additional inductance may be used in conjunction with the compensating condenser.

50 In Fig. 3 the two tuned circuits L_1C_1 and L_2C_2 are coupled to separate aerial coupling inductances La^1 and La^2 respectively arranged in series. The switch S connects either tuned circuit to the valve input circuit according to which wave lengths it is desired to receive, the remaining tuned circuit functioning as a rejector circuit. Where the two wave lengths are not very widely separated each tuned circuit acts as a rejector in turn. In this arrangement, the aerial coupling inductances La^1 and La^2 may be made 55 small and the tuning inductances L_1 and L_2 large and a more selective circuit results. The values of the aerial coupling inductances must be so chosen that the impedance of the aerial circuit is suitable for either wave length when both inductances are in circuit. As previously described, the inductances must be separated so as to prevent interaction.

55 The arrangements hereinbefore set forth are of particular use when the receiver is situated near one transmitting station, and at a distance from another transmitting station, and difficulties are experienced in receiving the distant station, owing to interference from the near station. However, the arrangements are also of use when the signals received from the two stations are of approximately equal strength, and the two wave lengths are not widely separated.

60 Referring to Fig. 4, the tuned circuits L_1C_1 and L_2C_2 each consist of an inductance in series with a capacity, and are arranged in parallel to one another in a common aerial-earth circuit AE. Thermionic valve V is arranged for the purpose either of amplifying or detecting the received oscillations, and the grid of V is connected through a switch S to either of the two tuned circuits, as shown. The grid circuit of valve V is adapted to be connected across that part of one, or other, of the tuned circuits, which gives the greatest signal response, while, at the same time, the action is such that for the other tuned circuit, a minimum signal response is obtained.

It is assumed that the valve V is voltage-operated, and the grid circuit is connected across either of the inductances L_1 or L_2 in positions 1 and 2 of switch S. L_1C_1 is tuned 5 to one frequency, while L_2C_2 is tuned to another, which may be a neighboring frequency. In position 1, oscillations of the frequency to which L_1C_1 is tuned are impressed on the grid circuit of V, whilst the oscillations 10 which occur in L_2C_2 do not affect the grid circuit and consequently L_2C_2 acts as a rejector circuit to eliminate interference. In position 2 of switch S the functions of the circuits are reversed.

15 In Fig. 5 a modification of Fig. 4 is shown, in which L_2C_2 are arranged in parallel to one another, while L_1C_1 remain series-tuned. In this case, it is necessary to employ condenser K connected between the tuned circuits, the value of which is so adjusted that tuning either of the circuits L_1C_1 or L_2C_2 20 will not materially affect the other. In this arrangement is also shown a reaction coil L_r , which may be coupled to either of the 25 inductances L_1 or L_2 in well-known manner. If desired, two separate reaction coils can be employed.

Fig. 6 shows a modification, in which both the tuned circuits consist of inductances L_1L_2 30 in parallel with capacities C_1C_2 . Interaction between the two tuned circuits is prevented by means of the inductance L and the capacity K, connected as shown between the two tuned circuits and the aerial A. If desired, the circuit LK can be tuned to a third 35 wave length, and may act in a similar manner to the other tuned circuit in serving either as a receptor or rejector circuit to this third wave length. As shown, switch S is provided with three positions whereby any of 40 the three tuned circuits can be connected across the input circuit of valve V. The arrangement can therefore be operated on one of three wave lengths, as desired, by means 45 of switch S. In this case, it is necessary to tune circuit L_2C_2 to the highest frequency, LK to the intermediate frequency, and L_1C_1 to the lowest frequency.

If the third wave length is not required to 50 be received or eliminated, in this arrangement the lower and higher frequencies must be tuned in by circuits L_1C_1 and L_2C_2 respectively. The inductance L and condenser K then serve effectively as radio frequency impedances to the higher and lower frequencies 55 respectively.

In Fig. 7 is shown an arrangement where 60 additional selectivity is required due to the interference emanating from a local station and to the proximity of the two wave lengths. A method is employed in which the interfering signal is neutralized or balanced out by 65 suitably adjusting the coupling and phase between the coils L_1 and L_2 and connecting one side of the condenser C_2 through another

70 condenser K to the high potential end of the coil L_1 . It will be seen that oscillations set up in the aerial circuit L_1C_1 will be induced in the other circuit L_2C_2 by virtue of the coupling and connections of the two circuits, which will cancel out the E. M. F. normally impressed between the points marked X and Y.

To prevent the balancing process materially reducing the strength of the weaker signal, the modification shown in Fig. 8 is used. A third circuit $L_{1a}C_{1a}$ is connected directly across the input terminals of the detecting device X, Y, and is tuned to the same wave length as the aerial circuit L_1C_1 80 to receive the weaker signal.

85 It will be seen that there are two coupling points between the aerial circuit and input circuit, one through the condenser K, and the other through the circuit L_2C_2 by virtue of the coupling between L_1 and L_2 . It can be arranged in practice for one of these paths to offer a much higher impedance to the weaker or unbalanced signal than the other, so that it is impressed upon the detecting or 90 amplifying device at practically normal strength.

95 In Fig. 9 is shown an arrangement similar to that illustrated by Figs. 1 to 3, but modified to enable closely adjacent frequencies to be received alternately. In this case, a compromise is effected between a series and parallel arrangement of the two tuned circuits by including a part only of the inductances L_1 and L_2 in the aerial circuit. The arrangement, however, is similar to the arrangements hereinbefore described, in that neither of the tuned circuits are short-circuited by the switch in either of its two 100 positions.

105 While, in general, the invention has been described in its application to the reception on two alternative wave lengths, the possibility of modifying the arrangements illustrated so as to render them suitable for the reception on more than two wave-lengths, the circuits not in use for reception serving to absorb or reject the undesired signals, should not be overlooked, and it is intended that the claims hereof should be construed 110 with this possibility in view.

What I claim as new and desire to secure by Letters Patent of the United States, is:

1. In a radio receiving system, a plurality 115 of tuned input circuits and means whereby at least one of the said circuits may be utilized alternatively as a receiver or a rejector circuit.

120 2. In a radio receiving system, an input circuit, a plurality of tuned circuits coupled to said circuit, and a switching arrangement whereby one of said tuned circuits may be connected in said circuit so as to function alternatively as either a receiving circuit for the system or a rejecting circuit for the fre- 125

quency to which another of said tuned circuits is responsive.

3. A radio receiving apparatus comprising an aerial circuit, a plurality of tuned circuits coupled to said aerial circuit and each tuned to one of the wave lengths it is desired to receive, a switching device for connecting one of said circuits so that it functions as a receiving circuit for the wave length to which it is tuned while another of said tuned circuits functions as a rejecting circuit for said wave length and for altering the connections so that the functions of said tuned circuits are reversed.

4. In a radio receiving system, an aerial circuit, two circuits each tuned to a different frequency and associated with said aerial circuit, an electrical valve, and means for connecting said valve to said tuned circuits so that a maximum signal response is given to said valve by one tuned circuit while a minimum response is given by the other tuned circuit which functions to absorb signal energy of the frequency to which it is tuned thereby substantially to eliminate interference from that frequency, said means being arranged to change the connections between said valve and said tuned circuits in such a manner that the functions of the two circuits are reversed.

5. A circuit arrangement for receiving radio signals on alternative wave lengths comprising an aerial system, a plurality of circuits each tuned to one of the desired wave lengths and coupled to said system, an electrical valve provided with input terminals, and a switch arranged to connect said input terminals to said aerial system so that in one position of the switch a maximum signal response is given by one tuned circuit while a minimum signal response is given by the other tuned circuit, and in another position of the switch the connections are such as to reverse the functions of the tuned circuits.

6. A radio receiving arrangement including a receiving device, an aerial circuit which contains two tuned circuits connected in series, and a switch arranged in one position to short circuit one of said tuned circuits and connect the other circuit to said receiving device, and in the other position to remove the short circuit and connect both of said circuits to the receiving device.

7. In a radio receiving system, a plurality of tuned input circuits, means whereby one of said circuits may be utilized alternatively as a receiver and a rejector circuit, and compensating means arranged to be connected across one of said tuned circuits.

In witness whereof, I have hereunto set my hand this 24th day of August, 1927.

THOMAS H. KINMAN.
